UNITED STATES PATENT OFFICE.

HERBERT W. HOOVER, OF NEW BERLIN, OHIO, ASSIGNOR TO THE HOOVER SUCTION SWEEPER COMPANY, OF NEW BERLIN, OHIO, A CORPORATION OF OHIO.

BRUSH-DRIVING DEVICE FOR SUCTION-CLEANERS.

1,309,093.

Specification of Letters Patent.

Patented July 8, 1919.

Application filed June 8, 1917. Serial No. 173,448.

To all whom it may concern:

Be it known that I, HERBERT W. HOOVER, a citizen of the United States, residing at New Berlin, in the State of Ohio, have invented a certain new and useful Improvement 5 in Brush-Driving Devices for Suction-Cleaners, of which the following is a specification.

My invention relates to improvements in 10 brush driving devices for suction cleaners and has for one object to provide a new and improved apparatus for driving the brush of a suction cleaner from the motor which drives the suction fan. Another object 15 is to provide a new and improved device for reducing the speed of the brush so that a light weight high speed motor may be used without unduly increasing the speed of the brush and without making the apparatus so bulky and clumsy as to be unsatisfactory in use. Other objects will appear 20 from time to time in the specification. My invention is illustrated more or less diagrammatically in the accompanying drawings, wherein—

Figure 1 shows a bottom plan view with parts removed;

Fig. 2 shows a section along the line 2—2 of Fig. 1;

Fig. 3 is a section along the line 3—3 of Fig. 1 with parts omitted.

Like parts are indicated by like characters in all the figures.

A is a suction nozzle; A¹ a suction chamber 35 communicating with the nozzle and discharging into a fan chamber A³ all being contained within an integral cast housing upon which is mounted a motor housing A⁴ containing a motor not here shown. This 40 motor drives the fan A⁵ which discharges dust-laden air through a passage A⁶ into a dust receptacle not here illustrated.

The motor shaft B which carries the fan A⁵ terminates in conical friction driving 45 member B¹ which engages the conical driving wheel B³. This conical driving wheel B³ is mounted upon a plate B⁴ on a sleeve B⁵, the sleeve B⁵ being slidably mounted and held against rotation about the shaft B⁶. B⁷ is a pin passing through the shaft B⁶ engaging a slot B⁸ in the sleeve. This pin holds the sleeve 50 against rotation with respect to the slot. It also furnishes an abutment for a collar B⁹

against which presses a spring B¹⁰ which 55 spring tends to yieldingly hold the wheel B³ against the wheel B¹ so as to make a yielding friction connection between the two wheels. It will be observed that the wheel B¹ is of much smaller diameter than the 60 wheel B³ so that the wheel B³ rotates at a lower rate of speed than does the part B¹.

C is a housing located within the housing A¹. It has an opening as at C² surrounded by and inclosed by a flange C³ on the wheel hub so as to prevent the entrance of dust and dirt. It contains the shaft B⁶, wheels, 65 springs and associated parts. It is closed outside the casing by a cover C⁴ held in position by the screws C⁵, and having air 70 inlet holes C¹². This cover has a bearing C⁶ in which the outer end of the shaft B⁶ is rotatably mounted. The cover C⁴ has a pocket C⁷ containing the ball C⁸ against which the shaft B⁶ is thrust by the spring 75 to make a thrust bearing. The opposed end of the shaft is mounted in a bearing C⁹ in the wall of the housing C. It carries on its end a pulley C¹⁰.

D is a brush rotatably mounted in the 80 suction nozzle. It is provided with a pulley D¹ over which travels an open belt D² which travels also around the pulley C¹⁰ so that rotation of the pulley drives the brush. The lower part of the suction chamber A¹ is 85 apertured as indicated in Fig. 1 and this aperture is closed by a metallic cap or plate D³. This metallic cap or plate is held in position by lugs D⁴ on the inner side by a spring finger D⁵ radially or diametrically 90 opposed thereto and engaging the inner side of the housing and by a spring finger D⁶ having a lug D⁷ to engage a notch D⁸ in the wall of the outside of the housing. The purpose of the opening is of course to enable 95 the operator to get at the belt and pulley to make the necessary adjustments to put the belt on or off the pulley and also so that he may get at the speed reduction and take it down.

It will be evident that while I have shown in my drawings an operative device, still many changes might be made both in size, shape and arrangement of parts without departing materially from the spirit of my invention, and I wish therefore that my drawings be regarded as in a sense diagrammatic.

The use and operation of my invention are as follows:—

This apparatus is intended to be used for cleaning floors and floor coverings in the usual manner. The brush beats and sweeps the floor covering, and the fan causes the suction which picks up the dust and dirt. The suction is of course strong enough to clean alone and the brush action would clean alone. When they coöperate we have a suction cleaner which is much more satisfactory than either would be alone.

The motor drives the fan and by the friction reduction gear as shown drives also the horizontal shaft parallel with the brush shaft at a lower rate of speed. This horizontal shaft carries a pulley smaller than the pulley on the brush and so the brush travels at a lower rate of speed than does the horizontal shaft. We thus have a double reduction in speed between the motor and the brush and the motor may be speeded up so as to give a better suction and the brush will still run slow enough so as to produce the desired result upon the floor covering and so as not to be unduly worn away.

The small chamber which carries the reduction or jack shaft I have termed a transmission chamber. It is mounted in and made an integral part of the whole casing. It is open, however, on the outside and closed by an outside separate closure which may be removed for the purpose of removing the jack shaft.

The bearings for the jack shaft and the whole transmission chamber are effectually kept free from dust and dirt and all clogging of the parts is prevented by the current of air drawn inwardly through the transmission chamber. This air current enters in through the aperture or perforation in the cover or cap which closes the outside opening of the transmission chamber. It passes in then along the jack shaft and finally discharges into the suction chamber or into the fan chamber through and around the bearing adjacent the driving belt and through and around the space or opening through which the conical driving wheel on the end of the fan shaft penetrates.

This arrangement has the further advantage of taking the twist out of the belt.

I claim:—

1. A suction cleaner comprising a casing

having an inlet and outlet and intermediate connected brush and fan chambers comprising a suction system for the passage of dust laden air, in combination with a brush, a fan, a motor, and power transmission devices connecting the motor and brush and a casing which incloses the bearings of such power transmission devices and is provided with one opening to the open air and another to the suction system.

2. A suction cleaner comprising a casing having an inlet and outlet and a brush chamber, a fan chamber and intermediate them a suction chamber, the whole comprising a suction system for the passage of dust laden air in combination with a brush, a fan, a motor and power transmission device connected to the motor and brush and a casing located within the suction chamber and inclosing the bearings of such power transmission device and provided with one opening to the open air and another to the suction system.

3. In a suction cleaner the combination of a casing with a brush, a fan and a motor contained therein, a jack shaft, a driving shaft, a speed reducing transmitting connection between the jack shaft and the driving shaft and a separate speed reducing transmitting connection between the jack shaft and the brush and a chamber which incloses the bearings of said jack shaft and is provided with one opening to the open air and another to the casing.

4. In a suction cleaner the combination of a casing with a brush, a fan and a motor contained therein, a jack shaft substantially parallel with the brush, a driving shaft substantially at right angles to the jack shaft, a speed reducing transmitting connection between the jack shaft and the driving shaft and a separate speed reducing transmitting connection between the jack shaft and the brush and a chamber which incloses the bearings of said jack shaft and is provided with one opening to the open air and another to the casing.

In testimony whereof, I affix my signature in the presence of two witnesses this 4th day of June, 1917.

HERBERT W. HOOVER.
